UNITED STATES PATENT OFFICE

2,377,357

STOKER

George Molotzak, Coaldale, Pa.

Application May 10, 1943, Serial No. 486,364

2 Claims. (Cl. 110—32)

The present invention relates to new and useful improvements in stokers and has for its primary object to provide a reciprocable feed plate adapted for feeding the coal from a hopper onto a fire plate or grate and progressively feeding the coal across the fire plate while being consumed.

A further object is to provide an apparatus of this character of simple and practical construction, which is efficient and reliable in performance, relatively inexpensive to manufacture and maintain in operation and otherwise well adapted for the purposes for which the same is intended.

Other objects and advantages reside in the details of construction and operation as more fully hereinafter described and claimed, reference being had to the accompanying drawing forming part hereof, wherein like reference numerals refer to like parts throughout, and in which:

Figure 1 is a longitudinal sectional view.

Figure 2 is a sectional view taken on a line 2—2 of Figure 1, and

Figure 3 is a sectional view taken on a line 3—3 of Figure 1.

Referring now to the drawing in detail, the numeral 5 designates a hopper having an inclined rear wall 6 at the lower end of which is the discharge opening for feeding coal onto a feed plate 7. The feed plate extends horizontally forwardly into a housing 8 projecting from the front wall of the hopper, the feed plate being spaced below the top of the housing.

A bearing 9 is formed on the underside of the feed plate for slidably mounting on a pair of rods 10 having their rear ends supported in a bracket 11 and their front ends supported by the rear wall of a chamber 12. A removable perforated fire plate or grate 13 is supported flush with the top of the chamber on ribs 13' formed on the inner walls of the chamber and on which the coal is burned. Projecting from the rear upper edge of the chamber 12 is a shelf 14 and on which is slideable the down-turned flange 15 on the front end of the feed plate 7 constituting a pusher for moving the coal forwardly on the fire plate.

Beneath the inclined rear wall 6 of the hopper is an electric motor (not shown) enclosed in a housing 16 for driving an eccentric 17 through suitable gearing in the housing 16. The eccentric is connected to the underside of the rear of the feed plate 7 by a pitman 18 for reciprocably actuating the feed plate.

A blower 19 is also connected to one side of the motor housing 16 for supplying a draft of air to the chamber 12 through a pipe 20.

Accordingly coal is fed by gravity onto the rear

end of the feed plate 7 from the hopper, the coal being moved forwardly on the feed plate during reciprocation of the latter by its engagement with the rear inclined wall 6 of the hopper.

5 From the front end of the feed plate the coal drops onto the fire plate 13 where it is burned, and is gradually moved toward the front edge of the latter by the pusher 15 and the ashes discharged from the front edge of the fire plate into a suitable receptacle.

The quantity of coal fed to the fire plate is controlled by a check plate 21 supported between spaced upstanding flanges 22 in the top of the housing 8 and secured in vertically adjusted position by a set screw 23.

A discharge pipe 25 is connected to the bottom of the chamber 12 by means of which fine ashes may be blown from the chamber.

Suitable control valves (not shown) may be provided in the pipes 20 and 25.

Having thus described the invention, what is claimed as new is:

1. A stoker comprising a hopper having a forwardly and downwardly inclined rear wall and a vertical front wall terminating in a plane above the lower edge of said rear wall, a housing having a flat horizontal top wall extending forwardly from the lower edge of said front wall, a chamber directly at the front of said housing having a stationary horizontal perforated fire plate at the top thereof disposed in a plane below that of the top wall of the housing, a flat horizontal shelf extending rearwardly from said chamber flush with said fire plate, a flat horizontal feed plate 35 extending from side to side of said housing and disposed in spaced parallel relation to and below the top wall of the latter, said feed plate contacting the lower edge of the rear wall of said hopper and having a downturned flange at its front end 40 slideable solely on said shelf entirely in advance of said hopper for pushing the coal forwardly from the shelf onto and across the fire plate when the feed plate is moved forwardly, and means to reciprocate said feed plate whereby coal is forced off of the forward end of the latter onto the shelf in advance of said flange upon rearward movement of said feed plate, said top wall of the housing having upstanding spaced transverse flanges, a check plate disposed between said flanges and vertically adjustable below said top wall to control the thickness of the forwardly fed layer of coal on said feed plates, and means to secure said check plate in any vertically adjusted position thereof.
2. A stoker comprising a hopper having a for-

wardly and downwardly inclined rear wall and a vertical front wall terminating in a plane above the lower edge of said rear wall, a housing having a flat horizontal top wall extending forwardly from the lower edge of said front wall, a chamber directly at the front of said housing having a stationary horizontal perforated fire plate at the top thereof disposed in a plane below that of the top wall of the housing, a flat horizontal shelf extending rearwardly from said chamber flush with said fire plate, a flat horizontal feed plate extending from side to side of said housing and disposed in spaced parallel relation to and below the top wall of the latter, said feed plate contacting the lower edge of the rear wall of said hopper and having a downturned flange at its

5 front end slidable solely on said shelf for pushing the coal forwardly from the shelf onto and across the fire plate when the feed plate is moved forwardly, and means to reciprocate said feed plate whereby coal is forced off of the forward end of the latter onto the shelf in advance of said flange upon rearward movement of said feed plate, a bracket mounted below the feed plate, a pair of spaced parallel guide rods supported in a horizontal position below said feed plate by said bracket and the rear wall of said chamber, and a slide bearing fixed to the under side of said feed plate intermediate the ends of the latter and slidably engaging said guide rods.
